Ex Ira Milton Jones
Esq

UNITED STATES PATENT OFFICE

FRANK R. BELLUCHE, OF RACINE, WISCONSIN

BRONZING MACHINE

Application filed June 13, 1928. Serial No. 285,034.

This invention relates particularly to a means for independently driving the cleaning rolls of a bronzing machine.

Heretofore, in bronzing machines and the like, it has been customary to drive the cleaning rolls from some portion of the machine itself and as the drive for the machine in most instances is taken from the press with which the machine is being used, it will be readily apparent that this mode of driving the rolls greatly impairs their efficiency as their speed varies in proportion to the speed at which the machine is being run. It being desirable that the cleaning rolls of a bronzing machine revolve at a constant predetermined speed independent of the speed of the machine which may be "inched" or run slow for certain types of work, it is therefore, an object of this invention to provide means for driving the cleaning rolls of a bronzing machine independently of the machine per se.

Another object of this invention resides in the provision of means for driving the cleaning rolls of a bronzing machine which utilizes the prime mover or motor by which the exhauster is driven.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawing, I have illustrated one complete example of the physical embodiment of my invention constructed according to the best mode I have so far devised for the practical application of the principles thereof, and in which:

The single view is a side elevational view of the gear side of a bronzing machine, parts being broken away and in section to illustrate structural details.

Referring now more particularly to the accompanying drawing, in which like numerals designate like parts, 5 designates the gear side frame of a bronzing machine of that

type described in my copending application, Serial No. 285,030 filed June 13, 1928 and 6 the feed side frame thereof. Bronzing machines of this type are usually placed so as to receive work directly from the press over tapes 7 from where it is picked up by a bronzing cylinder 8 to be carried past a bronzing roll or brush 9 which deposits bronzing material carried in a bin or trough 10 onto the work. A bronzing pad 11 rubs the bronze into the work as it passes therebeneath and a series of cleaning rolls 12 rapidly rotated in a direction opposite to the direction of movement of the work by means to be later described, remove the excess bronze which is drawn from the interior of the machine by an exhauster 13 through a passage 14.

After passing the cleaning rolls 12, the work is transferred from the bronzing cylinder to a delivery cylinder 15, on which the under surface of the sheet or work is cleaned by a cleaning roll 16 before the sheet is deposited onto the delivery tapes 17 to be discharged into a receiving box 18, or delivered in any other suitable manner.

As is customary, the drive for the bronzing machine is taken directly from the press, not shown, with which the machine is used so that the bronzing machine travels at a speed proportionate to the speed of the press, the drive being obtained by means of a belt 18 passed about a pulley, not shown, carried by the press and a drive pulley 19 fixed to a main drive shaft 20. The shaft 20 is suitably journaled in bearings carried by the frame 5 and a bearing member 21, and has mounted thereon a drive pinion 22 which meshes with a ring gear 23 carried by the delivery cylinder 15, a similar ring gear 24 being secured to the bronzing cylinder so that the pinion 22 drives the cylinders 15 and 8. As the speed at which the cleaning roll 16 is driven, does not affect the quality of the work, as it merely cleans the under side thereof, it receives its drive through an idler 25 meshing with the ring gear 23 and with a pinion 26 carried by its shaft 27.

The cleaning rolls 12, however, operate directly on the surface of the work and to function properly must be driven at a con-

stant predetermined speed and to this end each shaft 28 of the cleaning rolls has secured thereto a sprocket pinion 29 with which an endless sprocket chain 30 is drivingly connected, the chain passing over the sprocket of the lowermost roll 12 and then below an idler sprocket 31, upwardly over the sprocket of the middle cleaning roll, around the sprocket of the uppermost roll and downwardly again to mesh with a drive sprocket 32 secured to a shaft 33. From the sprocket 32 the chain extends downwardly around an adjustably mounted idler 34 which is provided with screw means 35 for maintaining the chain taut.

The shaft 33 has mounted thereon outwardly of the sprocket 32 another sprocket 36 about which a chain 37 is trained to be driven thereby from a motor 38 having a drive sprocket 39 meshing with the chain. The chain 37 is also trained about the drive sprocket 40 of the exhauster 13 and forms substantially a triangle with the sprockets 36, 39 and 40 forming the apexes thereof.

25 The motor 38 is mounted on a base 41 which is hingedly supported at one end from a stud or shaft 42 carried by the frame 5 so that the weight of the motor is supported entirely by the sprocket chain 37 and thus maintains the same taut and in engagement with its sprockets.

30 From the foregoing description taken in connection with the accompanying drawing, it will be readily apparent to those skilled in the art to which an invention of this character appertains that I provide a drive for the cleaning rolls of a bronzing machine which is entirely independent of the drive for the machine per se and one in which the speed of the rolls is at all times maintained at a constant predetermined value to assure the efficient operation thereof.

35 What I claim as my invention is:

1. In a bronzing machine, a work carrying means, means for driving the work carrying means to carry the work through the machine, means for depositing bronzing material onto the work, means for rubbing the bronzing material into the work, cleaning rolls for removing excess bronzing material from the work, an exhauster for withdrawing the bronzing material from the machine, sprockets carried by the cleaning rolls, a sprocket chain drivingly connecting the 40 sprockets of the cleaning rolls, a drive sprocket for said sprocket chain, means for driving the exhauster, and means whereby said exhauster drive drives the drive sprocket of the cleaning rolls whereby the cleaning rolls are driven at a constant predetermined speed irrespective of the speed of the bronzing machine per se.

2. In a bronzing machine, work carrying means, means for driving said means to carry the work through the machine, means for

depositing bronzing material onto the work, cleaning means for removing excess bronzing material from the work, an exhauster, an exhauster drive, and means for driving the cleaning means from the exhauster drive independently of the drive for the work carrying means.

70 In testimony whereof I have hereunto affixed my signature.

FRANK R. BELLUCHE.
